UNITED STATES PATENT OFFICE.

RALPH H. STAPLES, OF MOUNT VERNON, INDIANA.

BURNER.

Application filed February 24, 1923. Serial No. 620,982.

To all whom it may concern:

Be it known that I, RALPH H. STAPLES, a citizen of the United States, residing at Mount Vernon, in the county of Posey and 5 State of Indiana, have invented new and useful Improvements in Burners, of which the following is a specification.

This invention relates to a burner for burning oil, the general object of the invention being to provide a burner of simple construction and which may be so constructed that it can be used in cook stoves, furnaces and the like.

Another object of the invention is to so 10 form the parts that the flames will be forced against the walls of the fire box and to make the parts removable so that the burner can be easily cleaned.

Another object of the invention is to provide the burner with a wick of asbestos so 15 that the fuel is easily lighted.

This invention also consists in certain other features of construction and in the combination and arrangement of the several 20 parts, to be hereinafter fully described, illustrated in the accompanying drawings and specifically pointed out in the appended 25 claim.

In describing my invention in detail, reference will be had to the accompanying 30 drawings wherein like characters denote like or corresponding parts throughout the several views, and in which:—

Figure 1 is a view with parts in section 35 showing the invention in use in a cook stove.

Figure 2 is a longitudinal sectional view through the burner itself.

Figure 3 is a plan view of Figure 2 with part of the cover broken away.

Figure 4 is a section on line 4—4 of Figure 2.

Figure 5 is an elevation of a burner for use in a furnace.

Figure 6 is a sectional view through such 45 furnace.

Figures 7 and 8 are detail views.

As shown in Figure 1 the burner A is placed in the fire box B of the stove and the burner is connected by the pipes C with an 50 oil tank D, the parts being so arranged that the oil will be fed to the burner by gravity. The supply of oil to the burner is controlled by the valve E. The burner used in a cook stove is of substantially rectangular shape while that used in a furnace is of circular

shape. The burner A comprises a base 1 which is formed with a trough 2, the inner wall of the trough being formed by a flange 3 which forms the outer wall of a groove 4 which is adapted to contain a wick 5 of asbestos or the like. A pair of elongated openings 6 are formed in the device so as to permit air to pass from the point below the bottom of the device to the top thereof, the walls of the opening being extended to provide the flanges 7 which extend to a considerable distance above the base proper. The inlet pipe 8 extends through the base at the center thereof and is arranged between the air openings, this pipe being connected with the delivery pipes C. The cover 9 is provided with the projections 10 which engage the outer ends of the walls of the air openings so that the cover is supported above said openings and the wick with its flange 70 directly over the flange 3 though spaced from said flange.

From the above it will be seen that when the valve is open the oil will flow from the pipe 8 into the wick groove 4, thus saturating the wick 5. The valve is kept open until the wick groove overflow into the trough in the base. The valve is then closed and a match applied to the wick. After the burner 75 has been lighted a few seconds the valve 80 can be opened again and by regulating the flow of oil to the burner by this valve the flame of the burner can be controlled. The parts are so constructed that the blaze from the burner will be directed against the walls 85 of the fire box and attention is called to the fact that there are no parts to interfere with this flame.

When the device is to be used in a furnace it is made of round construction, as 90 shown in Figures 5 and 6, only one air port 6' being used and this being circular and located in the middle of the device. The inlet port 8' is located adjacent one side of the wick groove. The cover in this construction is also of circular shape, as shown at 9' and it is provided with projections 10' which engage the upper part of the wall of the air port 6'. The action of this device 100 is the same as those before described.

As will be seen the device is extremely simple, and as the cover can be lifted off, the burner can easily be kept clean. It can also be lighted by placing a lighted match 105 adjacent the wick.

The oil groove encircles the air intake so that perfect combustion is insured and as the wick is located in the groove it is very easy to light the burner. As the burner becomes hot the oil automatically changes to gas. The burner is very easily cleaned as it is only necessary to lift the reflector or cover and brush the burner to remove carbon and the like.

10 It is thought from the foregoing description that the advantages and novel features of my invention will be readily apparent.

I desire it to be understood that I may make changes in the construction and in the 15 combination and arrangement of the several parts, provided that such changes fall within the scope of the appended claim.

What I claim is:—

A burner of the class described comprising a base having a vertically arranged air 20 passage therein, a flange formed on the upper portion of the base and forming a continuation of the air passage, a groove formed in the base adjacent the flange, a wick, in said groove, a trough formed in the 25 base, between the groove and the periphery of the base, said trough being deeper than the groove, a flanged cover, projections thereon engaging the top of the flange to support the cover in spaced relation to the flange and 30 means for delivering oil to the wick groove.

In testimony whereof I affix my signature.

RALPH H. STAPLES.
